STEEL CAR CONSTRUCTION

**Charles J. Scudder and Edwin M. Jenkins,
Scranton, Pa.**

Application August 21, 1935, Serial No. 37,226

4 Claims. (Cl. 105—409)

This invention relates to steel railroad car construction, the characteristic features of the invention being adapted for the construction of box cars, ventilated box cars, house, automobile and other cars. A principal object of the invention is to provide a strong and rigid car construction that is relatively of light weight and with a minimum number of parts. To this end we provide a construction which continues each of the sides of the car to form one-half of the car top, the abutting extremities of the respective combined side and top portions being united at the transverse center of the car top by novel securing and reinforcing means. A further object is to provide improved means to ventilate the car effectively, the ventilating provision being effective between the inside lining and the outer steel sheathing. A still further object is to provide means for effectively carrying off condensed moisture which tends to collect on the inside of the outer steel sheathing of the car and other exposed parts, such formation of condensed moisture being particularly experienced when the cars are loaded with warm products, such as hot flour that later cools down to the roadway temperatures. The distinctive features of our invention are adapted to be applied as an improved type of body to any usual or suitable steel under structure of the car. It is to be understood that our invention is adapted only to the building of new cars, but to the re-building of existing cars to provide our improved

Figure 6 is an enlarged sectional detail on line 6-6 of Figure 2.

Figure 7 is an enlarged sectional detail on line 7-7 of Figure 1.

Figure 8 is an enlarged sectional detail on line 8-8 of Figure 1; and

Figure 9 is an enlarged sectional detail of the central top portion as shown in Figure 2 and illustrating more particularly the provision for securing the two combined side and top portions of the car together and the mounting of the runway thereover.

10 indicates generally the under-frame structure of the car which may be of usual or suitable either built-up or unit steel construction. 11 denotes the side sills of the under-frame. To these sills horizontally extending Z-bars 12 are secured. In carrying out our invention we provide a series of upright spaced apart Z-bars 13 which constitute the reinforcing frame work of the car body being suitably spaced apart as required for proper reinforcement along the length of the car. It is to be here understood that elsewhere reference is made to Z-bars, in the description of the body structure, this reference is to be understood as illustrative and not restrictive and structural bars of any suitable cross-section may be employed. The Z-bars 13 are secured at their lower ends by suitable angle brackets or the like 14 to the horizontally extending Z-bars 12.

body or upper construction. The foregoing and other objects and advantages of the invention will be better understood from the following detailed description taken in connection with the accompanying drawings, and the distinctive features of novelty will be thereafter pointed out in the appended claims.

In accordance with our invention the Z-bars 13 are of a length so as to not only extend up the sides of the car body but half-way over the top as indicated at 13a, being for this purpose curved or bent at the car corners as indicated at 13b. The abutting extremities of these series of Z-bars indicated at 13c are secured together by suitable pins forming tie plates 14 so as to constitute a

Referring to the drawings: Figure 1 is a partial side elevation with portions broken away, of a car body embodying the invention.

Figure 2 is a transverse section also with portions broken away, on line 2-2 of Figure 1. Figure 3 is a fragmentary, longitudinal, vertical section on a relatively enlarged scale at the top of one end of the car and showing parts two sides, a reinforcing bar 15, illustratively shown as a T-bar, is secured. 16 denotes the outer steel sheathing of the car body which in accordance with our invention may also be formed as one steel plate for each side of the car, such plate extending up and being bent over the roof

50 particularly the provision for ventilation. Figure 4 is a partial detail plan view of the frame work to constitute the car roof. It is to be noted that we thus simplify and strengthen the 50 upper structure of the car with the elimination of the use of side plates customarily used in box

Figure 5 is an enlarged sectional detail of the ventilated box, house, or other cars and with our structure shown in the lower left hand corner of Figure 2. At the eaves of the car, we greatly strengthen the 55

body structure permitting also the body to be made much lighter while preserving the requisite strength. The roof portions 16a of the outer sheathing 16 terminate in accordance with our 5 invention, a small distance short of the transverse center of the car and their extremities are bent upward and outward to form flanges as indicated at 17 to support the running board 18. While the flanges 17 are shown as bent outward, 10 this is merely illustrative, and they might be bent inward within the contemplation of the invention. The spacing apart of the flanges 17 of the outer sheathing at the top of the car not only provides for the support of the running board but also is 15 a part of the provision for providing ventilation for the space between the outer sheathing of the car and the inner lining or sheathing 19. This ventilating provision comprises labyrinth castings 20 secured to the ends of the car top, the 20 reinforcing T-bar 15 being cut away as indicated at 15a to permit the location of these labyrinth castings. The running board 18 extends over these labyrinth castings and the labyrinth form thereof is such as to allow the air freely 25 to enter and escape but to largely exclude dust, cinders, and snow. It will be understood that the motion of the car will assist the circulation giving it direction to front or rear corresponding to the movement of the car. Since the air channel 30 thus formed under the running board is continuous from end to end and connects at the top with all of the spaces formed between the outer and inner sheathings, and the Z-bar supports of the sides of the car, free circulation of air will be 35 set up. Such circulation of air is further insured and promoted by the provision of the troughs 20 at the base of the sides of the car where the vertical Z members are united to the side sills, between the side sills and the side sheathing for 40 the full length of the car at this point. The trough 20 thus formed, also serves to collect the condensed moisture that forms on the roof and side sheets of the car which will flow downwardly and collect therein. A suitable number of holes 45 21 may be produced in the horizontal portion of the Z-bars 12 to permit such moisture to escape. Holes 22 may be provided in the webs of the side channels at the bases thereof to further facilitate the escape of the water. At the ends of the side 50 sills somewhat larger holes 23 may be provided, arranged to be plugged if desired and adapted to permit the application of means to clean out the side troughs by air or water as may be desired. At the locality of the car doors, the Z-bars 13 55 at each side of the door extend the same as the others, with suitable bars shown as U bars 24, extending across the top of the door opening and suitably secured to the Z-bars 13. The ends of the car may be provided with usual outer sheathing 60 fluted or otherwise formed for reinforcing effect as indicated at 25. As herein indicated, the running board 15 may be formed as a steel plate, the intermediate, transverse portion of which is supported by the rib of the T-bar 15. 65 It is to be noted that our improved construction of running board including the upwardly and outwardly turned flanges 17 at each side thereof, provides a convenient handhold extending the length of the car that may readily be grasped by a 70 person who might slip while on the running board or roof, to protect himself. As herein shown, the inner sheathing 19 is of wood as desirable for box cars, but of course any suitable lining material may be used. The labyrinth ventilators

20 is to be understood as merely illustrative and intended to typify any suitable form of louvres, shutters or like devices adapted to be fitted at the ends of the passage underneath the running-board 18 to obstruct the entrance of foreign 5 matter.

In the foregoing as well as other aspects, the present embodiment of the invention, is to be understood in all respects as illustrative and not restrictive, reference being had to the appended 10 claims rather than to the foregoing description to indicate the scope of the invention.

Having now described our invention, what we claim as new and desire to secure by Letters Patent is:

1. A steel car construction comprising an under frame having side sills, upright frame members secured to said sills having extensions bent inward towards each other to abutting relation and secured together to constitute supports for the 20 sides and roof of the car, continuous sheathing secured to said frame members at each side also bent inward over said frame bars to form the roof, said sheathing terminating in upwardly and then horizontally turned extremities short of the 25 transverse center of the car, a runningboard resting upon and secured to the horizontal extremities of said sheathing constituting with such sheathing a unitary roof sheet for the car providing a ventilating channel extending the length 30 of the car, there being openings through the car ends registering with such channels, and an inner sheathing secured to said frame members, said ventilating channel serving to ventilate the space between the inner and outer sheathings in 35 the manner set forth.

2. A car construction comprising an under-framing equipped with side sills, upright frame work members secured to said sills and bent to continue inward forming the roof support with 40 their ends secured together, and inner and outer sheathings secured to said frame members forming continuous side and roof structures, said outer sheathing formed and having means associated therewith to provide continuous ventilating passages extending the length of the car to ventilate 45 completely the space between said sheathings, there being Z-bars fixed to the side sills with the upright frame bars secured to said Z-bars, said Z-bars and the outer sheathing constituting 50 lengthwise troughs to collect moisture with provision for the discharge thereof.

3. A steel car construction comprising an under frame, upright frame bars secured thereto having extensions bent inward towards each other with their ends abutting and secured together, a reinforcing angle bar extending over the junction of said ends and secured thereto, and a unitary roof sheet composed of sheathing secured to said frame bars terminating short of the transverse center of the car in upwardly and horizontally out-turned extremities and a running board secured to said out-turned extremities serving as a complement of said unitary roof sheet and spaced above said frame bars to provide 60 ventilation, there being openings in the car ends registering with the passage so formed.

4. A steel car construction as defined in claim 3, wherein said reinforcing angle bar serves as a support for the intermediate extent of the running board.

CHARLES J. SCUDDER.
EDWIN M. JENKINS.
